VARIABLE RESISTOR CONSTRUCTIONS

Marlan E. Bourns, Riverside, Calif.

Application May 3, 1954, Serial No. 427,326

2 Claims. (Cl. 201—62)

The present invention relates to new and improved variable resistor constructions.

For many present-day electronic applications it is necessary to have small compact, comparatively inexpensive, and dependable variable resistors. A large number of attempts have been made to produce such units, and to varying extents these attempts have proved somewhat successful. None of these prior efforts, however, have been so overwhelmingly accepted that efforts toward producing better variable resistors of a small size at a comparatively low cost have ceased.

It is an object of the present disclosure to teach the production of new and improved variable resistors which are more acceptable than the prior units designed to accomplish the same results by one or more of the criteria indicated above. More specifically, it is an object of the present invention to provide potentiometer and rheostat constructions which are dependable, small and compact, and comparatively simple to manufacture. Further objects of the present invention, as well as the advantages of it, will be apparent from the balance of this specification, the appended claims and the accompanying drawings in which:

Figure 1 is a side view of a variable resistor of the invention;

Figure 2 is a cross-sectional view taken at line 2—2 of Figure 1;

Figure 3 is a cross-sectional view taken at line 3—3 of Figure 2;

Figure 4 is a partial cross-sectional view taken at line 4—4 of Figure 2;

Figure 5 is another partial cross-sectional view taken at line 5—5 of Figure 2;

Figure 6 is an isometric view of a slider employed in the construction of Figure 1;

Figure 7 is an isometric view of a contact member which is carried by the slider shown in Figure 6;

Figure 8 is a cross-sectional view similar to Figure 3 of a modified variable resistor construction of the invention;

Figure 9 is a cross-sectional view similar to Figure 3 of a second modified variable resistor construction of the invention; and

Figure 10 is a partial cross-sectional view taken at line 10—10 of Figure 9.

Figure 11 shows a detail of the terminal connection of Figure 3.

In all figures of the drawings like numerals are used to designate like parts.

The present disclosure may be briefly summarized as being concerned with variable resistor constructions including a base member having a relatively flat upper surface, a cover positioned over said base member so as to be spaced generally from said flat upper surface, electrically conductive members disposed parallel to one another upon said upper surface, at least one of said electrically conductive members being of appreciable electrical resistance characteristics, a slider mounted between said

2

cover and said flat upper surface, spring contact means carried by said slider, means mounted for moving said slider and said spring contact member with respect to said upper surface so that said spring contact member is in constant engagement with said electrically conductive members, and terminal means projecting through said base member and being in electrical contact with said electrically conductive members.

More specifically it may be stated that this disclosure is concerned with potentiometer or rheostat constructions of the broad category indicated in the preceding paragraph in which a large number of structural innovations are employed to produce electrical components of the class described which are relatively inexpensive and easy to manufacture, which are comparatively small and compact and which are extremely dependable in operation. It is thought that the nature of these structural details will be best more fully explained by reference to the drawings accompanying this application. The various figures of the drawings are not necessarily drawn to scale, but are drawn in order to conveniently illustrate the details of the present invention.

Referring now to Figure 1 through 5 of the drawings, where it is seen that a variable resistor 10 of the invention includes a base 11 of an insulating material such as a filled phenol-formaldehyde resin having a substantially flat upper surface 12, and upstanding ends 14. The sides 15 of the base 11 are provided with notches 16 which lead past the ends of the upper surface 12 into the upstanding ends 14. Within these ends the notches 15 intersect with vertical notches 17. With this construction it is thus possible for sides 19 of a cover 20 formed of metal to be placed along the base 11 between the upstanding ends 14. These sides 19 are connected to a top 21 positioned generally parallel to the flat upper surface 12 between the ends 14 of the base 11. This top 21 is adapted to generally overlie the ends 14, and is adapted to be secured to these ends by means of fastening arms 22 attached to the top 21 adjacent to the ends 14 so as to lie within notches 23. Each of these notches 23 is intersected adjacent to the bottom 24 of the base 11 by another notch 25. The fastening arms 22 include dependent projections 26 which are designed to fit within these notches 25.

Normally sides 19, the arms 22 and the projections 26 are formed in such a manner that they grasp the base 11 with a spring-like or snap action preventing undesired displacement of the cover 20 with respect to this base 11. In order to secure a spring-like action of this category the cover 20 is preferably formed of a resilient metal. If desired auxiliary means such as eyelets passing through the sides 19 and the ends 14 can be utilized to position the cover 20 with respect to the base 11. When such means are employed it is not necessary to utilize fastening arms such as the arms 22.

The upper surface 12 of the base 11 is provided with a substantially square-shaped notch 30 which is adapted to hold an inverted U-shaped conductor 31, which serves as an electrical return means from the resistance element to a terminal, the sides of said conductor being urged against the sides of the notch 30 by means of the inherent resiliency of the material from which the conductor 31 is manufactured. Suitable materials for this purpose include Phosphor bronze, copper, etc. One side 60 of the conductor 31 is formed with a projecting terminal tab 32 which is adapted to lie within an opening 33 connecting the bottom 24 of the base 11 with the notch 30. With this construction the tab 32 is securely held with respect to the rest of the variable resistor 10.

The upper surface 12 of the base 11 is also provided with a notch 34 which is adapted to hold an insulating core 35 upon which there has been placed a spiral re-

sistance element 36. This resistance element 36 is normally held in place by means of terminal tabs 37 projecting through apertures 38 connecting the upper surface 12 and the bottom 24 of the base 11. These tabs 37 are preferably formed in a bent configuration 39 so that they are held within the apertures 38 adjacent the element 36 by spring tension. The tabs 37 may, if desired, be formed in specialized shapes corresponding to the shape of the resistance element 36 so as to aid in retaining this resistance element within the notch 34, or, if desired, may be cemented in position in addition to being held by spring tension. If desired the resistance element 36 can be pressed within this notch so as to be held in position by a "force-fit" type of action. The resistance element can also be held in position by various adhesives. If any portion of the resistance element adjacent to the tabs 37 is covered with an insulating coating this coating is, of course, removed before or during the assembly of the final device so as to establish electrical contact.

Between the cover 20 and the base 11 there is disposed a slider 40 formed of an insulating material such as a filled phenol-formaldehyde resin, such as is shown in Figure 6 of the drawings. This slider is designed to fit between the walls 19 and is provided with an internal threaded bore 41 and edge slots 42. These edge slots are adapted to carry curved projecting ears 43 of a spring member 44 of Phosphor bronze, stainless steel or the like such as is specifically shown in Figure 7. This spring member 44 also includes dependent curved contact members 45. When these ears 43 are held within the slots 42 of the slider 40 there is substantially no danger of the spring member 44 moving away from the slider 40; and the contact members 45 are spaced from the bottom of the slider 40. As is apparent from the drawings, the spring member 44 does not project beyond the confines of the slot 42 toward the walls 19 or the top 21 and is thus at all times insulated from these walls and this top.

The slider 40 is normally held in position with the contact members 45 being disposed against the uppermost portions of the U-shaped conductor 31 and the resistance element 36 by means of a shaft 50 having a threaded section 51 and smooth ends 52 and 53. The end 52 is normally located within a cavity 54 located in one of the ends 14; the other end 53 normally projects from the variable resistor 10 through a notch 56 formed in the other end 14; and the threaded section 51 carries the slider 40. The end 53 is adapted to be held in position within the notch 56 by edge projections 57 formed on the end 14 within the notch 56 and by means of a similar projection 58 formed on the top 21 of the cover 20 engaging a shoulder which may conveniently be provided by a circumferential groove 55 in the shaft 50. A projection 59 formed on the top 21 of the cover 20 is adapted to bear against the end 52 of the shaft 50. Both of these projections 58 and 59 are effective because of the inherent resiliency of the material from which they are made in controlling the tension on the shaft 50 so that all times a uniform amount of force is required to turn this shaft. These projections also serve to ground the shaft 50 to the cover 20. With the specific construction shown the slider 40 and the contact member 44 can be moved by rotating the shaft 50 so that the spring contacts 45 are placed in position against desired adjacent portions of the conductor 31 and the resistance element 36. Rotation of the slider 40 when the shaft 50 is rotated is prevented by projections or runners 63 extending downwardly from the side of the slider 40 adjacent to the base 11 and slidably engaging the exposed sides of the conductor 31. If desired such projections or lugs may be formed elsewhere on the slider 40 in order to engage other portions of the resistor 10 in order to accomplish the same result.

The modified construction shown in Figure 8 of the drawings differs from that shown in Figures 1 through 6 in that the conductor 31 and the resistance element 36

are replaced by a metal strip 64 and a parallel resistance member 60 disposed within slots 61 formed in the base 11. Any electrically conductive metal, such as, for example Phosphor bronze, copper, etc. can be used for the strip 59; and the member 60 can be formed of a suitable resinous resistance composition. Suitable compositions are known to the art and include mixtures of carbon black and phenolic resins. The construction shown in Figure 8 also differs from that of Figure 3 in that the terminal tabs 32 and 37 are replaced by terminal tabs 62 wedged within apertures 63' in the base 11 connecting the upper surface 12 with the bottom 24. The tabs 62 include bent over spring contact portions lying generally parallel to the upper surface 12 making contact with the upper surface of the strip 59 and the resistance member 60. With this specific construction the tab employed with the strip 59 is located adjacent to the end of this strip so as not to interfere with the movement of the slider 40.

In Figure 9 there is shown another modified construction which differs from the preceding variable resistors in that terminal tabs 65 are employed which are molded within the base 11 so as to project from both the upper surface 12 and the bottom 24. These tabs 65 are adapted to be secured to resistance films 66 positioned upon supporting insulating bases 67 dispersed within slots 68 by means of solder 69. These resistance films 66 can be of any resistance composition known to the art of producing printed circuit components; if desired these resistance films 66 can be placed directly upon the upper surface 12 of base 11. The construction shown in this figure is primarily designed to be employed as a rheostat. In order to prevent interference with the movement of the slider 40, the tabs 65 are preferably located adjacent to the ends of the resistance films 66. If desired a silver ink or other highly conductive film can be substituted for one of the resistance films 66.

The slider 40 employed with the modified construction shown in Figures 9 and 10 of the drawings differs from the slider 40 used with the other constructions previously indicated in that the bore 41 is not threaded and in that there is provided an internal cavity 71 which projects into the center portion of the slider 40 so as to be intersected in the bore 41 from adjacent to the top 21 of the cover 20. Disposed within the cavity 71 is a follower 72 formed of a resilient metal having sides 73 and 74 joined at an apex 75. Both of these sides 73 and 74 are provided with side openings 76 and 77 respectively which are of such a dimension that as the sides 73 and 74 are pulled together the shaft 50 may be readily inserted within the openings 76 and 77 without threading the shaft 50 through these openings. These openings 76 and 77 are also of such a dimension that once the shaft 50 and the follower 72 are positioned substantially as located the sides 73 and 74 may be released so as to allow at least part of one of these two openings to fit within the threads on the section 51 of the shaft 50. When the sides 73 and 74 have been released in this manner they engage edges 78 of the cavity 71 so as to wedge the follower 72 against the slider 40 in such a manner that as the shaft 50 is turned the slider 40 will be moved. This construction has the advantage of substantially eliminating backlash.

Both of the sides 73 and 74 terminate in bentover end sections 79 which engage the top 21 of the cover 20 on the side of the slider 40 remote from the spring member 44. These bentover end sections 79 are designed to exert a spring action upon the top 21 which will tend to prevent rotation of the slider 40 when the shaft 50 is rotated. In order to achieve this purpose the amount of force required to deform these ends 79 must be greater than the amount of force required to bend the curved contact members 45.

Those skilled in the art will realize that a number of modifications of the specific constructions shown can be made without departing from the broad teachings of this disclosure. As an example of such modifications, the

various conductive and resistance means shown can be substituted for one another although they are not to be considered as complete equivalents. Similarly the follower arrangement shown in Figure 10 can be substituted for the projections shown in Figure 3 and Figure 4, and such projections can be used in place of this follower arrangement in the construction of Figure 10, although these items are not strictly equivalents. Further, resistance films such as a metal resinate film on a cylindrical supporting surface can be substituted for the resistance element 36. It is also possible to form the tabs 32, 37, 62 and 65 in the form of plugs designed to fit mating sockets. All such modifications of this category are to be considered as part of the invention insofar as they are defined by the appended claims.

It is believed that the specific advantages of the various constructions indicated in this specification will be so obvious to those skilled in the art that it will be unnecessary to discuss them in detail. Constructions as herein shown and described can be manufactured comparatively cheaply, using a minimum number of parts and constitute a major improvement over the prior devices of a similar category presently being manufactured for this reason. Another major advantage of the invention lies in the fact that a wide variety of different resistance or conductive films can be utilized as desired in order to obtain any desired results. The terminal tabs illustrated can be easily formed in such a manner that they can be utilized in mounting the units of the invention.

I claim:

1. A device of the class described, comprising a body, an electrically conductive element mounted on said body, a slider positioned above said element and movable along the length thereof, a rotatable lead screw extending through said slider and having threaded engagement therewith, a pair of laterally spaced projections extending downwardly from the underneath side of said slider and engaging said device on opposite sides of said element, to prevent said slider from rotating with said lead

screw, and a contact carried by said slider, said contact engaging said electrically conductive element.

2. A variable resistor comprising a body, an elongated resistance element mounted on said body, a conductor strip mounted on said body alongside said resistance element, a slider positioned above said resistance element and conductor strip and movable along the length thereof, a rotatable leadscrew extending parallel to said resistance element, means on said slider engaging the threads of said leadscrew whereby said slider is moved lengthwise of said resistance element when the leadscrew is turned, a pair of laterally spaced runners extending downwardly from said slider and slidably engaging portions of said resistor on opposite sides of said element to prevent the slider from rotating with said leadscrew, and a contact on said slider wiping on said resistance element and said conductor strip.
